AUTOMATIC TRANSFER KNITTING MACHINE

Clarence W. Minton, Nashville, Tenn., assignor to May Hosiery Mills, Nashville, Tenn., a corporation of Tennessee

Application August 6, 1951, Serial No. 240,464

26 Claims. (Cl. 66—24)

This invention relates to textiles and more particularly to a method and apparatus for knitting hosiery.

In the knitting industry particularly in the knitting of hosiery it has been common practice to use rib knitting for the leg and plain knitting for the foot portion. These operations have commonly been performed on two separate machines one for the rib knitting which is termed "a ribber" and one for the plain knitting which is termed "a footer" with the knitted fabric being manually transferred from one machine to the other.

As is well known in the art, the rib knitting of hose may be performed on a machine utilizing a plurality of vertically reciprocable needles slidably mounted in grooves in the outer surface of a cylinder. These needles may be termed "cylinder needles" and which cooperate with a plurality of horizontal or dial needles which reciprocate radially in grooves in the upper surface of a dial or plate disposed above the upper end of the cylinder. In the simplest form of rib knitting the cylinder and dial needles are arranged alternately but any desired combination of cylinder and dial needles may be utilized in order to provide different rib patterns. Plain knitting is performed by the use only of the cylinder needles.

There are many disadvantages in this prior method of making hosiery among them being the fact that it is necessary to maintain a relatively large supply of ribbed tops in order that the plain knitting machines will always be kept busy. Also there are numerous problems connected with the shades or colors of the yarn utilized since it is almost impossible to knit the tops and foot portions of the hose from the same dye lot of yarn where this is done on different machines and it is likely that the tops will be knitted at one time and the foot portion at another time as much as several weeks or months later. Obviously it would not be practical to attempt to make all of these top portions and foot portions from the same dye lot of yarn, consequently, many problems having to do with shading are presented which have contributed materially to the relatively high cost of production. By production in the prior manner much yarn is wasted since it is necessary for the ribbed top to have extra or excessive length to make it possible for the operator to transfer the same to the plain knitting machine. Such extra or excessive length is unraveled or "raveled off" after the transfer operation is finished and such unraveled yarn is discarded or wasted.

One of the important objections to the present method of manually transferring from the rib knitting machine to the plain knitting machine is that a high degree of skill is required of the operator. Such skilled operators are relatively scarce and many persons do not have the necessary aptitude to permit their being trained as transfer operators. Consequently, the cost of such operation is materially increased and there is always the problem of obtaining sufficient trained operators to maintain production.

Heretofore numerous attempts have been made to eliminate the manually transfer operation including a ma-

chine which knits the stocking backwards or in other words from the toe to the top. Also relatively expensive special needles have been used which are designed to permit the cylinder needle to engage the loop carried on the dial needle and most of these required that very close tolerances in manufacturing be maintained and also as soon as a relatively small degree of wear had taken place in the parts breakage of needles occurred, stitches would drop and the resulting product was definitely inferior. These prior art machines present a very real problem of maintenance and much time has been lost due to frequent breakdowns.

It is therefore an object of this invention to provide a method and apparatus for automatically performing a transfer knitting operation.

Another object of this invention is to provide an automatic transfer knitting apparatus utilizing relatively inexpensive needles and in which it is not necessary to maintain extremely close tolerances, normal wear having no effect on the efficiency of the apparatus.

Another object of the invention is to provide an automatic transfer knitting apparatus in which the loop is carried by the dial needles is spread or enlarged to permit the cylinder needles to pass through and receive the loop from the dial needles in order to complete the transfer operation.

A further object of the invention is to provide an automatic transfer knitting apparatus which will produce knitted hosiery of high quality and with no apparent change in the knitting when compared with present commonly used manual methods.

A further object of the invention is to provide an automatic transfer knitting apparatus which may be economically constructed at a cost only slightly higher than the cost of conventional knitting machines.

A still further object of the invention is to provide a method of automatically transferring the stitches from the dial needles in the knitting machine to the cylinder needles thereof in order to produce completely knitted hose in one automatic operation and on a single machine.

Further objects and advantages of the invention will be apparent from the following description taken in conjunction with the accompanying drawings, wherein:

Fig. 37, a sectional view on the line 37—37 of Fig. 36.

Briefly stated the invention comprises means whereby a conventional knitting machine may be converted to a transfer knitting machine in which the loops carried by the dial needles are automatically transferred to the cylinder needles. The machine includes the conventional cylinder and needles carried thereby and a specially formed dial for carrying and operating the dial needles. This dial incorporates the usual grooves for carrying the needles but these grooves are machined at an incline so that the loop carried by these needles is spread apart or enlarged a greater distance than the normal thickness of the needle. In conventional operations the needles are disposed with their wider dimensions upright or vertical and the loops carried by such needles are separated only by the thickness of the needle.

With the needles disposed at an incline in the present invention the loops will be separated a distance determined by the width of the needles and the particular degree of incline utilized. This incline will normally be from approximately 15° to 20° from the vertical and will permit the formation of a relatively wide loop which serves to receive the cylinder needle when it is desired to transfer from the dial needles to the cylinder needles.

Means is provided in the form of a cam for actuating the dial needles when it is desired to transfer the stitches therefrom to the cylinder needles and suitable control means is provided for initiating this operation at the desired point in the knitting process.

With continued reference to the drawings there is shown in Fig. 1 a knitting machine constructed in accordance with the present invention and having a base 10 which serves to receive and rotatably support a gear 11 having an upstanding hollow hub 12. Mounted upon the hub 12 and rotatable therewith is a cylinder 13 which is secured against rotation relative to the gear 11 by pins 14 extending through the gear 11 and into apertures in the cylinder 13. Gear 11 is driven by a gear 15 mounted

upon a drive shaft 16 which may be actuated from any suitable source of power.

Cylinder 13 is provided with the usual grooves 17 for receiving cylinder needles 18 which are reciprocated vertically in the grooves 17 by conventional cam means not shown. Cylinder needles 18 as shown in Figs. 36 and 37 may comprise an elongated shank portion 19, a cam engaging butt 20 extending at right angles to the shank portions 19 at one end thereof, a reduced portion 21 connecting the shank 19 with a hook 22 the reduced portion 21 being chamfered or beveled as at 23 for a purpose to be later described. Pivoted slightly below the hook 22 is a latch 24 which serves to close the hook 22 when removing a stitch from the reduced portion 21 of the cylinder needle 18. With the exception of the beveled or chamfered portion 23 the cylinder needle 18 is constructed in substantially the same manner as conventional cylinder needles.

A bracket 25 is pivotally mounted on an upstanding portion of the frame or base end and bracket 25 serves to receive and support a sleeve 26 having an enlarged portion 27 at the lower end thereof to which is secured by screw threaded fastening means or the like 28 a cam supporting plate 29. Sleeve 26 also serves to rotatably receive a shaft 30 on the lower end of which is fixed, a dial 31. The specific structure of dial 31 will be presently described. Fixed to the upper end of shaft 30 is a bevel gear 32 which meshes with a bevel gear 33 carried by a shaft 34 journaled in bearings 35 on the bracket 25. The opposite end of shaft 34 carries a bevel gear 36 which meshes with a bevel gear 37 carried by a vertical shaft 38 journaled in bearings 39 mounted on the frame 10. Shaft 38 is connected to a suitable power source and serves to drive the dial 31.

Due to the pivotal mounting of bracket 25 the dial 31 and associated mechanism may be moved out of the way when it is necessary to make repairs or adjustments to the mechanism and as is shown in Fig. 1 bracket 25 and mechanism carried thereby may be moved to operative position with the bevel gear 36 engaging the bevel gear 37 and bracket 25 may be latched in operative position by a latch bolt 40 slidably mounted in a bracket 41 secured to the frame 10, latch bolt 40 being reciprocated by an eccentric pin 42. The upper end of latch bolt 40 is provided with a rotatably mounted button 43 which is secured to the bolt 40 by screw threaded fastening means or the like 44, button 43 when rotated to one position passing through a slot 45 in a member 46 attached to the bracket 25 and when button 43 is rotated 90° the same will serve to engage the upper surface of member 46 and upon rotation of eccentric pin 42 to move the latch bolt 40 downwardly, the bracket 25 and associated mechanism will be locked in operative position.

With particular reference to Figs. 2 to 4 the dial 31 comprises a disk 47 having a plurality of radial grooves formed in the upper surface thereof, disk 47 having a central hub 49 provided with an aperture 50 for receiving the shaft 30. Hub 49 is also provided with a keyway 51 for engaging a key 52 received in a recess in the shaft 30 and in the opposite side of the hub 49 there is provided a set screw 53 for securely clamping the hub 49 and the dial 31 on the shaft 30. As best shown in Fig. 3, the grooves 48 in the upper surface of dial 31 are inclined from the vertical and serve to receive and position dial needles therein in a manner and for a purpose to be presently described. As best shown in Fig. 2, a recess 54 is provided in the upper dial surface of the outer end of each radial groove 48 to provide clearance for the needle.

As best shown in Figs. 1, 5, 6, 7, and 8 the cam supporting plate 29 serves to support movable needle actuating cams 55, 56, and 57. Plate 29 likewise carries fixed cams 58 and 59 which serve to reciprocate the dial needles in a direction opposite to that caused by the cams 55, 56, and 57. Cams 55, 56, and 57 are mounted upon shafts 76 extending through enlarged portion 27 carried by sleeve

26 and the shafts are actuated by levers 60 which are pivotally connected to cam actuating arms 61. Arms 61 are operated by suitable mechanism which will cause actuation of the cams 55, 56, and 57 in accordance with the pattern being knitted by the machine. Cams 55, 56, and 57 cause outward movement of the needles received in the grooves 48 of dial 31 and fixed cams 58, and 59 caused inward movement of such needles in a manner to be presently described.

Several different forms of dial needles 62 are shown in the drawing and these needles will be described with particular reference to Figs. 24 to 35 inclusive. As shown in Figs. 24, 25, 26, and 27 needles 62 may comprise a relatively wide body portion 63 having at one end thereof an offset resilient tang or tail 64. When needle 62 is received in grooves 48 of dial 31 the tang 64 is substantially straight and serves to provide a sufficient tension to retain the needle 62 in proper position in the dial groove 48. The body 63 of needle 62 is provided with a butt 65 which may be either of the length shown in full lines in Fig. 25, or may be somewhat longer as shown in dotted lines in the same figure. Also, body 63 of needle 62 is provided with a tapered concave groove 66 the purpose of which will be presently described. At the opposite end of needle 62 from the tang 64 there is provided a reduced portion 67 terminating in a hook 68. In order to close the hook 68 during knitting operations, a latch 69 is mounted on a pivot 70 on the reduced portion 67, the latch 69 having a forward hood 71 which, as shown in Fig. 27, partially embraces the inner end of the hook 68 for a purpose to be later described. At the point of juncture between the body 63 and reduced portion 67 there is provided a shoulder 72 connected to the reduced portion by an inclined surface 72' which together with the shoulder 72 serves to engage a loop of yarn in a manner and for a purpose which will be described in connection with the description of the operation of the apparatus.

In Figs. 28, 29, 30 and 31, there is shown a slightly modified form of dial needle 62 which is identical in every respect to the needle described above except that the reduced portion 67 which terminates in the hook 68 is provided with a bend or twist 73 in order that the hook 68 will occupy a vertical position in spite of the fact that the body 63 of the needle 62 is inclined to the vertical by reason of the inclined grooves 48 in the dial 31.

A still further modified form of dial needle 62 is shown in Figs. 32, 33, 34, and 35 and in this form the only change from the needle described above in connection with Figs. 24 to 27 is the fact that the butt 65 is bent as clearly shown in Fig. 35 to occupy a vertical position when the body 63 of the needle 62 is received in the inclined groove 48 of dial 31.

The disposition and operation of the dial needles 62 is best shown in Figs. 5 to 11 and from an inspection of these figures it will be seen that the needles 62 are disposed in grooves 48 of the dial 31 for radial sliding movement, such movement being effected during the knitting operation by cam 55 and during the transfer operation by the cams 56 and 57. One half of the needles disposed in the dial grooves are provided with relatively long butts 65 and the other half are provided with short butts. The long and short butts are necessary in order to properly carry out the transfer operation as will later appear.

The dial 31 with needles 62 disposed in the grooves 48 thereof rotates in a counterclockwise direction when viewed from the top of the apparatus and cam supporting plate 29 is stationary. With the cams 55, 56, and 57 in the position shown in Fig. 6 the needles 62 will be retracted to their innermost position in the dial 31 and in this neutral position the dial needles 62 will not operate to knit fabric. This is the position which the dial needles 62 will occupy after the transfer operation and during the plain knitting step.

When it is desired to knit the ribbed portion of a sock, cam 55 will be moved to the position shown in

Figs. 7 and 9 by operation of the appropriate arm 61 at which time needles 62 will be progressively moved outwardly in the grooves 48 of dial 31 by engagement of the butts 65 with the edge of cam 55. As shown in Fig. 9 the needles 62 move outwardly until they have passed the outer end of cam 55 at which time the butts 65 engage fixed cam 58 carried by plate 29 which serves to move the needles 62 inwardly to retracted position. The needles 62 remain in this position until they have completed one revolution when the butts 65 again engage cam 55 to move the needles outwardly and form another stitch.

During the rib knitting operation the cylinder needles 18 which are located directly below the dial needles 62 are idle the rib portion of the sock being formed by every other cylinder needle and by the dial needles. Upon completion of this ribbed portion it is necessary to transfer the stitches which are carried by the dial needles 62 to the previously idle cylinder needles 18. This operation is accomplished by means of the cams 56 and 57 in a manner as shown in Figs. 8, 10 and 11.

As will be seen from an inspection of the above figures cams 56 and 57 operate in a manner similar to knitting cam 55 with the exception that during the transfer operation the needles 62 are projected a greater distance out of the dial than they were during the knitting operation. As previously stated, one half of the needles 62 in dial 31 are provided with high butts 65 and the remaining needles are provided with low butts. As shown in Fig. 10 at the start of the transfer operation cam 57 is moved outwardly by operation of the proper arm 61 cam 57 serving to engage only those needles provided with high butts. As the dial 31 rotates carrying the needles 62 in a counterclockwise direction as viewed from the top of the machine the high butts 65 contact the edge of cam 57 and the needles 62 are moved outwardly to the position shown in Fig. 10. The needles 62 are retracted into the dial grooves by engagement of the butts 65 with fixed cam 59 carried by plate 29. Upon completion of one half of a revolution of the dial 31 during the transfer operation, the cam 56 is moved outwardly as shown in Fig. 11 this cam serving to engage the needles 62 provided with low butts and thus complete the transfer operation by transferring the stitches from all of the dial needles 62 to the alternate cylinder needle 18. Upon completion of the transfer operation the cams 56 and 57 are moved to the neutral position shown in Fig. 6 and the dial needles 62 are not utilized again until the plain knitting of the sock has been completed and it is desired to start the rib top of another sock. Stitch loops 74 engage the reduced portion 67 of needles 62 and a strand of yarn 75 is engaged by the hooks 22 of alternate cylinder needles 18. In the position shown in Fig. 12 the dial needle 62 is projected to cast off or knitting position at which time the loop 74 is to the rear of the opened latch 69. Upon retraction of the dial needle 62 into the dial 31 the hook 68 engages the strand of yarn 75 and pulls the same through a loop 74 which as best shown in Fig. 13 slides over the closed latch 69 to the position shown in Fig. 14 the strand of yarn 75 serving to form the loop of a second stitch. It is to be understood that loops of yarn are likewise received on alternate cylinder needles 18 and that stitches are formed by pulling addition loops of the strand of yarn 75 through the loops received on the needles 18 in the same manner as that described above in connection with the dial needle 62. During this operation, the cylinder needle 18 located between the outer cylinder needles as shown in Figs. 12, 13, and 14 remains in a lowered inoperative position as shown in these figures the rib knitting operation being performed on the alternate cylinder needles and all of the dial needles 62.

When it is desired to transfer the stitch loops 74 carried by the dial needles 62 to the previously idle cylinder needles 18 it is necessary for such cylinder needles to move upwardly and pass through the loops 74 carried by the dial

needle 62 in order to receive the same on the shank of the cylinder needle below the latch 24. The instant invention is designed to facilitate this operation by spreading the loop 74 to provide ample space for passage of the cylinder needle 18. Such spreading of the loops 74 is accomplished by the inclined disposition of the dial needles 62 and their action in connection therewith is best shown in Figs. 19 to 22. As will be seen from an inspection of these figures the loop 74 passes over the inclined needle and due to such inclination the effective width of the needle is increased thereby increasing the width of the loop. This can be readily understood when compared with Fig. 23 in which is shown a conventional needle disposed in a vertical position and with a loop 74 disposed thereon. Obviously, such loop is only separated by the thickness of the needle 62 which results in insufficient space being provided for passage of the cylinder needle 18 during a transfer operation. The transverse dimension of the loop 74 received on the needle 62 will be substantially equal to the projected width of the inclined needle 62.

The transfer operation will now be described with reference to Figs. 15 to 22 inclusive. In Fig. 15 the dial needle 62 is partially projected to initiate the transfer operation with the loop 74 moving rearwardly on the reduced portion 67 and up the inclined surface 72' to occupy a position as shown in Fig. 16 with the loop 74 engaging the shoulder 72 to pull the loop outwardly of the dial and stretch the same slightly. At this time the loop as clearly shown in Fig. 16 is disposed across the concave tapered groove 66 in the dial needle 62 in a position approaching parallelism with the longitudinal axis of the needle. Also as seen in Fig. 15 the previously idle cylinder needle 18 has started to move upwardly and as shown in Fig. 16 this cylinder needle has partially passed through the loop 74. The cylinder needle continues to move upwardly until it reaches the position shown in Fig. 17 at which time the loop 74 carried by the dial needle 62 is disposed about the shank 21 of the cylinder needle 18 below the latch 24. Also as shown in Fig. 17 the dial needle 62 is partially retracted and the loop 74 is shown as about to pass off such needle over the latch 69. On completion of the inward movement of dial needle 62 the loop 74 formally carried thereby will be entirely disengaged therefrom and received on the shank 21 of the cylinder needle 18. Upon complete withdrawal of the dial needle 62 the cylinder needle 18 moves downwardly and at the same time the hook 22 thereof engages the strand of yarn 75 and pulls a loop of the same through the loop 74 just transferred to this needle from the dial needle and forms a further stitch. This initiates the plain knitting operation and such operation continues for the desired length of fabric.

The operation of the cylinder needle 18 during the transfer operation is best shown in Figs. 19 to 22 inclusive, Fig. 19 showing the relative positions of the cylinder needles 18 and dial needles 62 prior to the transfer operation and Fig. 20 showing their relative positions at the start of such operation with the hook 22 of the cylinder needle 18 engaging the concave tapered groove 66 in the inclined dial needle 62 just prior to passing through the loop. Fig. 21 shows the cylinder needle 18 after passing through the loop 74 and the manner in which the cylinder needle is deflected by the inclined surface of the dial needle 62. Fig. 22 shows the cylinder needle 18 in its extreme uppermost position and also shows the purpose and operation of the chamfered or beveled edge 23 of the needle 18.

Since the needle 18 is deflected by the inclined dial needle 62 and since the cylinder needle 18 passes upwardly and engages the dial needle 62 within the concave tapered groove 66 and further since the dial needles 62 are retracted when the cylinder needle 18 is in the position shown in Fig. 22 the beveled or chamfered edge 23 is provided to prevent damage to the needles during the retraction of dial needles 62. If a sharp edge were

presented by the cylinder needle 18 the same would tend to bite into the edge of needle 62 adjacent the concave groove 66 and cause damage thereto. Likewise the chamfered or beveled surface 23 prevents damage to the latch 69 of the dial needle 62 during retracting movement thereof, since obviously this latch will be engaged by the edge of cylinder needle 18 when in the position shown in Fig. 22.

As will be seen from an inspection of Fig. 17 the loops 74 in passing over the latch 69 of dial needle 62 will tend to pull the same side ways or transversely of the needle since there is an appreciable downward pull on the loop 74 and when utilizing the form of dial needle shown in Figs. 24 to 27 the latch is inclined with respect to the vertical and consequently a downward pull on the loop 74 would exert a transverse bending force on the latch 69. Consequently the hood 71 as best shown in Figs. 25 and 27 is provided to reinforce the latch 69 since with the hood 71 in engagement with the end of hook 68 a support therefor is provided to prevent lateral movement of the latch 69.

If desired the dial needle 62 shown in Figs. 28 to 31 may be utilized in which case the latch and hook portion of the needle is twisted to be disposed in a vertical position and in such position, of course, the downward tension on the loop 74 will not tend to move the latch 69 laterally of the needle. Consequently with this form of the needle it is not necessary to provide a hood to assist in supporting the latch 69.

It will be seen that by the above described invention there has been provided a relatively simple and economically constructed machine for automatically transferring stitch loops from dial needles to cylinder needles when it is desired to change from rib knitting to plain knitting and one in which relatively inexpensive dial needles may be utilized. Extremely close tolerances need not be maintained in manufacture and the simplicity of the device materially contributes to long wear and lack of frequent breakdowns.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. In an automatic transfer knitting machine a base, a cylinder rotatably mounted on said base, vertical grooves in the outer surface of said cylinder, cylinder needles slidably disposed in said grooves, certain of said cylinder needles reciprocating during a rib knitting operation and all of said cylinder needles reciprocating during a plain knitting operation, a dial disposed above the upper end of said cylinder and mounted for rotation about a vertical axis, radial grooves in the upper surface of said dial, dial needles slidably disposed in said radial grooves, means operable upon rotation of said dial to reciprocate said dial needles during a rib knitting operation and to retract said dial needles to an inoperative position during a plain knitting operation, said radial grooves and said dial needles being inclined to the vertical whereby the transverse dimension of stitch loops received on said dial needles will be substantially equal to the projected width of said dial needles, each of said dial needles comprising an elongated relatively thin body of appreciable width, a cam engaging butt extending from one edge of said body, a reduced portion extending from one end of said body and terminating in a yarn engaging hook, a latch pivotally mounted on said reduced portion and engageable with said hook to close the same, a hood on said latch partially embracing said hook when in closed position to prevent bending of said latch out of the plane of said hook, a shoulder on the end of said body adjacent said reduced portion, an upwardly inclined surface extending from said reduced portion to said shoulder

and a tapered concave groove in the lower inclined surface of said body adjacent said shoulder, and cam means movable into progressive engagement with the butts of said dial needles to progressively move said dial needles outwardly of said dial a greater distance than during a rib knitting operation whereby a stitch loop received on said reduced portion will move up said inclined surface into engagement with said shoulder and upon continued outward movement of said dial needles said loop will be disposed across said concave groove in a position approaching the horizontal thereby permitting upward movement of certain of said cylinder needles into engagement with the walls of said concave grooves and through the loops disposed across said grooves whereby upon retraction of said dial needles the loops carried thereby will be transferred to said certain cylinder needles.

2. In an automatic transfer knitting machine a base, a cylinder rotatably mounted on said base, vertical grooves in the outer surface of said cylinder, cylinder needles slidably disposed in said grooves, certain of said cylinder needles reciprocating during a rib knitting operation and all of said cylinder needles reciprocating during a plain knitting operation, a dial disposed above the upper end of said cylinder and mounted for rotation about a vertical axis, radial grooves in the upper surface of said dial, dial needles slidably disposed in said radial grooves, means operable upon rotation of said dial to reciprocate said dial needles during a rib knitting operation and to retract said dial needles to an inoperative position during a plain knitting operation, said radial grooves and said dial needles being inclined to the vertical, whereby the transverse dimension of stitch loops received on said dial needles will be directly proportional to the angle of inclination of said dial needles, each of said dial needles comprising an elongated relatively thin body of appreciable width, a cam engaging butt extending from one edge of said body, a reduced portion extending from one end of said body and terminating in a yarn engaging hook, a latch pivotally mounted on said reduced portion and engageable with said hook to close the same, a shoulder on the end of said body adjacent said reduced portion, an upwardly inclined surface extending from said reduced portion to said shoulder and a tapered concave groove in the lower inclined surface of said body adjacent said shoulder and cam means movable into progressive engagement with the butts of said dial needles to progressively move said dial needles outwardly of said dial a greater distance than during a rib knitting operation, whereby a stitch loop received on said reduced portion will move up said inclined surface into engagement with said shoulder and upon continued outward movement of said dial needles said loop will be disposed across said concave groove in a position approaching the horizontal thereby permitting upward movement of certain of said cylinder needles into engagement with the walls of said concave grooves and through the loops disposed across said grooves whereby upon retraction of said dial needles the loops carried thereby will be transferred to said certain cylinder needles.

3. An apparatus as defined in claim 1 in which a portion of said cylinder needle which contacts the wall of said concave groove is chamfered in order to provide a smooth sliding engagement therebetween.

4. An apparatus as defined in claim 2 in which a portion of said cylinder needles which contacts the wall of said concave groove is chamfered in order to provide a smooth sliding engagement therebetween.

5. In an automatic transfer knitting machine a base, a cylinder rotatably mounted on said base, vertical grooves in the outer surface of said cylinder, cylinder needles disposed in said grooves, certain of said cylinder needles reciprocating during a rib knitting operation

and all of said cylinder needles reciprocating during a plain knitting operation, a dial disposed above the upper end of said cylinder and mounted for rotation about a vertical axis, radial grooves in the upper surface of said dial, dial needles slidably disposed in said radial grooves, means operable upon rotation of said dial to reciprocate said dial needles during a rib knitting operation and to retract said dial needles to an inoperative position during a plain knitting operation, said radial grooves and said dial needles being inclined to the vertical, whereby the transverse dimension of stitch loops received on said dial needles will be substantially equal to the projected width of said dial needles, each of said dial needles comprising an elongated relatively thin body of appreciable width, a cam engaging butt extending from one edge of said body a reduced portion extending from one end of said body and terminating in a yarn engaging hook, a latch pivotally mounted on said reduced portion and engageable with said hook to close the same, a shoulder on the end of said body adjacent said reduced portion, an upwardly inclined surface extending from said reduced portion to said shoulder and a tapered concave groove in the lower inclined surface of said body adjacent said shoulder and cam means movable into progressive engagement with the butts of said dial needles to progressively move said dial needles outwardly of said dial a greater distance than during a rib knitting operation, whereby a stitch loop received on said reduced portion will move up said inclined surface into engagement with said shoulder and upon continued outward movement of said dial needles said loop will be disposed across said concave groove in a position approaching the horizontal thereby permitting upward movement of certain of said cylinder needles into engagement with the walls of said concave grooves and through the loops disposed across said grooves whereby upon retraction of said dial needles the loops carried thereby will be transferred to said certain cylinder needles.

6. In an automatic transfer knitting machine a base, a cylinder rotatably mounted on said base, vertical grooves in the outer surface of said cylinder, cylinder needles slidably disposed in said grooves, certain of said cylinder needles reciprocating during a rib knitting operation and all of said cylinder needles reciprocating during a plain knitting operation, a dial disposed above the upper end of said cylinder and mounted for rotation about a vertical axis, radial grooves in the upper surface of said dial, dial needles slidably disposed in said radial grooves, means operable upon rotation of said dial to reciprocate said dial needles during a rib knitting operation and to retract said dial needles to an inoperative position during a plain knitting operation, said radial grooves and said dial needles being inclined to the vertical, whereby the transverse dimension of stitch loops received on said dial needles will be directly proportional to the angle of inclination of said dial needles, each of said dial needles comprising an elongated relatively thin body of appreciable width, a cam engaging butt extending from one edge of said body, a reduced portion extending from one end of said body and terminating in a yarn engaging hook, a latch pivotally mounted on said reduced portion and engageable with said hook to close the same, a shoulder on the end of said body adjacent said reduced portion, an upwardly inclined surface extending from said reduced portion to said shoulder and a tapered concave groove in the lower inclined surface of said body, adjacent said shoulder and cam means movable into progressive engagement with the butts of said dial needles to progressively move said dial needles outwardly of said dial a greater distance than during a rib knitting operation, whereby a stitch loop received on said reduced portion will move up said inclined surface into engagement with said shoulder and upon continued outward movement of said dial needles

said loop will be disposed across said concave groove in a position approaching the horizontal thereby permitting upward movement of certain of said cylinder needles into engagement with the walls of said concave grooves and through the loops disposed across said grooves whereby upon retraction of said dial needles the loops carried thereby will be transferred to said certain cylinder needles.

7. In an automatic transfer knitting machine a base, a cylinder rotatably mounted on said base, vertical grooves in the outer surface of said cylinder, cylinder needles slidably disposed in said grooves, certain of said cylinder needles during a rib knitting operation, and all of said cylinder needles reciprocating during a plain knitting operation, a dial disposed above the upper end of said cylinder and mounted for rotation about a vertical axis, radial grooves in the upper surface of said dial, dial needles slidably disposed in said radial grooves, means operable upon rotation of said dial to reciprocate said dial needles during a rib knitting operation and to retract said dial needles to an inoperative position during a plain knitting operation, said radial grooves and said dial needles being inclined to the vertical whereby the transverse dimension of stitch loops received on said dial needles will be substantially equal to the projected width of said dial needles, each of said dial needles comprising an elongated relatively thin body of appreciable width, a cam engaging butt extending from one edge of said body, a reduced portion extending from one end of said body and terminating in a yarn engaging hook, a latch pivotally mounted on said reduced portion and engageable with said hook to close the same, a shoulder on the end of said body adjacent said reduced portion and a tapered concave groove in the lower inclined surface of said body adjacent said shoulder and cam means movable into progressive engagement with the butts of said dial needles to progressively move said dial needles outwardly of said dial a greater distance than during a rib knitting operation, whereby a stitch loop received on said reduced portion will move into engagement with said shoulder and upon continued outward movement of said dial needles, said loop will be disposed across said concave groove in a position approaching the horizontal thereby permitting upward movement of certain of said cylinder needles into engagement with the walls of said concave grooves and through the loops disposed across said grooves whereby upon retraction of said dial needles the loops carried thereby will be transferred to said certain cylinder needles.

8. In an automatic transfer knitting machine a base, a cylinder rotatably mounted on said base, vertical grooves in the outer surface of said cylinder, cylinder needles slidably disposed in said grooves, certain of said cylinder needles reciprocating during a rib knitting operation, and all of said cylinder needles reciprocating during a plain knitting operation, a dial disposed above the upper end of said cylinder and mounted for rotation about a vertical axis, radial grooves in the upper surface of said dial, dial needles slidably disposed in said radial grooves, means operable upon rotation of said dial to reciprocate said dial needles during a rib knitting operation and to retract said dial needles to an inoperative position during a plain knitting operation, said radial grooves and said dial needles being inclined to the vertical whereby the transverse dimension of stitch loops received on said dial needles will be directly proportional to the angle of inclination of said dial needles, each of said dial needles comprising an elongated relatively thin body of appreciable width, a cam engaging butt extending from one edge of said body, a reduced portion extending from one end of said body and terminating in a yarn engaging hook, a latch pivotally mounted on said reduced portion and engageable with said hook to close the same, a shoulder on the end of said body adjacent said reduced portion and a tapered concave groove in the lower inclined surface of said body adjacent said shoulder and cam means movable into progressive

engagement with the butts of said dial needles to progressively move said dial needles outwardly of said dial a greater distance than during a rib knitting operation, whereby a stitch loop received on said reduced portion will move into engagement with said shoulder and upon continued outward movement of said dial needles said loop will be disposed across said concave groove in a position approaching the horizontal thereby permitting upward movement of certain of said cylinder needles into engagement with the walls of said concave grooves and through the loops disposed across said grooves whereby upon retraction of said dial needles the loops carried thereby will be transferred to said certain cylinder needles.

9. In an automatic transfer knitting machine a base, a cylinder rotatably mounted on said base, vertical grooves in the outer surface of said cylinder, cylinder needles slidably disposed in said grooves, certain of said cylinder needles reciprocating during a rib knitting operation and all of said cylinder needles reciprocating during a plain knitting operation, a dial disposed above the upper end of said cylinder and mounted for rotation about a vertical axis, radial grooves in the upper surface of said dial, dial needles slidably disposed in said radial grooves, means operable upon rotation of said dial to reciprocate said dial needles during a rib knitting operation and to retract said dial needles to an inoperative position during a plain knitting operation, said radial grooves and said dial needles being inclined to the vertical whereby the transverse dimension of stitch loops received on said dial needles will be substantially equal to the projected width of said dial needles, each of said dial needles comprising an elongated relatively thin body of appreciable width, a cam engaging butt extending from one edge of said body, a reduced portion extending from one end of said body and terminating in a yarn engaging hook, a latch pivotally mounted on said reduced portion and engageable with said hook to close the same, a shoulder on the end of said body adjacent said reduced portion and cam means movable into progressive engagement with the butts of said dial needles to progressively move said dial needles outwardly of said dial a greater distance than during a rib knitting operation, whereby a stitch loop received on said reduced portion will move into engagement with said shoulder and upon continued outward movement of said dial needles said loop will be disposed in a position approaching the horizontal thereby permitting upward movement of certain of said cylinder needles into engagement with the lower inclined surface of said body and through said loops whereby upon retraction of said dial needles the loops carried thereby will be transferred to said certain cylinder needles.

10. In an automatic transfer knitting machine having a cylinder, cylinder needles carried by said cylinder and reciprocable axially thereof, a dial disposed adjacent one end of said cylinder at right angles to the axis thereof, dial needles carried by said dial and reciprocable outwardly and toward the axis of said dial, said dial needles being inclined to the axis of said dial, whereby the transverse dimension of stitch loops received on said dial needles will be substantially equal to the projected width of said dial needles, each of said dial needles comprising an elongated relatively thin body of appreciable width, a butt extending from one edge of said body, a reduced portion extending from one end of said body and terminating in a yarn engaging hook, a latch pivotally mounted on said reduced portion and engageable with said hook to close the same, a hood on said latch partially embracing said hook when in closed position to prevent bending said latch out of the plane of said hook, a shoulder on the end of said body adjacent said reduced portion, an inclined surface extending from said reduced portion to said shoulder and a tapered concave groove in the inclined surface of said body toward said dial and adjacent said shoulder and means movable into progressive engagement with the butts of said dial needles to

progressively move said dial needles outwardly of said dial, whereby a stitch loop received on said reduced portion will move up said inclined surface into engagement with said shoulder and upon continued outward movement of said dial needles said loop will be disposed across said concave groove in a position approaching right angles to the axis of said dial thereby permitting axial movement of certain of said cylinder needles into engagement with the walls of said concave grooves and through the loops disposed across said grooves whereby upon retraction of said dial needles the loops carried thereby will be transferred to said certain cylinder needles.

11. In an automatic transfer knitting machine having a cylinder, cylinder needles carried by said cylinder and reciprocable axially thereof, a dial disposed adjacent one end of said cylinder at right angles to the axis thereof, dial needles carried by said dial and reciprocable outwardly and toward the axis of said dial, said dial needles being inclined to the axis of said dial whereby the transverse dimension of stitch loops received on said dial needles will be substantially equal to the projected width of said dial needles, each of said dial needles comprising an elongated relatively thin body of appreciable width, a butt extending from one edge of said body, a reduced portion extending from one end of said body and terminating in a yarn engaging hook, a latch pivotally mounted on said reduced portion and engageable with said hook to close the same, a shoulder on the end of said body adjacent said reduced portion, an inclined surface extending from said reduced portion to said shoulder and a tapered concave groove in the lower inclined surface of said body toward said dial and adjacent said shoulder and means movable into progressive engagement with the butts of said dial needles to progressively move said dial needles outwardly of said dial, whereby a stitch loop received on said reduced portion will move up said inclined surface into engagement with said shoulder and upon continued outward movement of said dial needles said loop will be disposed across said concave groove in a position approaching right angles to the axis of said dial thereby permitting axial movement of certain of said cylinder needles into engagement with said concave grooves and through the loops disposed across said grooves whereby upon retraction of said dial needles the loops carried thereby will be transferred to said certain cylinder needles.

12. In an automatic transfer knitting machine having a cylinder, cylinder needles carried by said cylinder and reciprocable axially thereof, a dial disposed adjacent one end of said cylinder at right angles to the axis thereof, dial needles carried by said dial and reciprocable outwardly and toward the axis of said dial, said dial needles being inclined to the axis of said dial whereby the transverse dimension of stitch loops received on said dial needles will be substantially equal to the projected width of said dial needles, each of said dial needles comprising an elongated relatively thin body of appreciable width, a butt extending from one edge of said body, a reduced portion extending from one end of said body and terminating in a yarn engaging hook, a latch pivotally mounted on said reduced portion and engageable with said hook to close the same, a shoulder on the end of said body adjacent said reduced portion and a tapered concave groove in the inclined surface of said body toward said dial and adjacent said shoulder and means movable into progressive engagement with the butts of said dial needles to progressively move said dial needles outwardly of said dial, whereby a stitch loop received on said reduced portion will move into engagement with said shoulder and upon continued outward movement of said dial needles said loop will be disposed across said concave groove in a position approaching right angles to the axis of said dial thereby permitting axial movement of certain of said cylinder needles into engagement with the walls of said concave grooves and through the loops dis-

posed across said grooves whereby upon retraction of said dial needles the loops carried thereby will be transferred to said certain cylinder needles.

13. In an automatic transfer knitting machine having a cylinder, cylinder needles carried by said cylinder and reciprocable axially thereof, a dial disposed adjacent one end of said cylinder at right angles to the axis thereof, dial needles carried by said dial and reciprocable outwardly and toward the axis of said dial, said dial needles being inclined to the axis of said dial whereby the transverse dimension of stitch loops received on said dial needles will be substantially equal to the projected width of said dial needles, each of said dial needles comprising an elongated relatively thin body of appreciable width, a butt extending from one edge of said body, a reduced portion extending from one end of said body and terminating in a yarn engaging hook, a latch pivotally mounted on said reduced portion and engageable with said hook to close the same, a shoulder on the end of said body adjacent said reduced portion and means movable into progressive engagement with the butts of said dial needles to progressively move said dial needles outwardly of the dial whereby a stitch loop received on said reduced portion will move into engagement with said shoulder and upon continued outward movement of said dial needles said loop will be disposed in a position approaching right angles to the axis of said dial thereby permitting axial movement of certain of said cylinder needles into engagement with the inclined surfaces of said bodies facing said cylinder and through said loops whereby upon retraction of said dial needles the loops carried thereby will be transferred to said certain cylinder needles.

14. In an automatic transfer knitting machine having a cylinder, cylinder needles carried by said cylinder and reciprocable axially thereof, a dial disposed adjacent one end of said cylinder at right angles to the axis thereof, dial needles carried by said dial and reciprocable outwardly and toward the axis of said dial, said dial needles being inclined to the axis of said dial, whereby the transverse dimension of stitch loops received on said dial needles will be substantially equal to the projected width of said dial needles, each of said dial needles having a shoulder thereon whereby upon outward movement of said dial needles a stitch loop carried thereby will move into engagement with said shoulder and be disposed in a position approaching right angles to the axis of said dial thereby permitting axial movement of certain of said cylinder needles into engagement with the inclined surfaces of said needles facing said cylinder and through said loops whereby upon retraction of said dial needles the loops carried thereby will be transferred to said certain cylinder needles.

15. In an automatic transfer knitting machine having a cylinder, cylinder needles carried by said cylinder and reciprocable axially thereof, a dial disposed adjacent one end of said cylinder at right angles to the axis thereof, dial needles carried by said dial and reciprocable outwardly and toward the axis of said dial, said dial needles being inclined to the axis of said dial whereby the transverse dimension of stitch loops received on said dial needles will be directly proportional to the angle of inclination of said dial needles, each of said dial needles having a shoulder thereon whereby upon outward movement of said dial needles a stitch loop carried thereby will move into engagement with said shoulder and upon continued outward movement of said dial needles said loop will be disposed in a position approaching right angles to the axis of said dial thereby permitting axial movement of certain of said cylinder needles into engagement with the inclined surfaces of said needles facing said cylinder and through said loops whereby upon retraction of said dial needles the loops carried thereby will be transferred to said certain cylinder needles.

16. In an automatic transfer knitting machine having a cylinder, cylinder needles carried by said cylinder and

reciprocable axially thereof, a dial disposed adjacent one end of said cylinder at right angles to the axis thereof, dial needles carried by said dial and reciprocable outwardly and toward the axis of said dial, said dial needles being inclined to the axis of said dial whereby the transverse dimension of stitch loops received on said dial needles will be substantially equal to the projected width of said dial needles, thereby permitting axial movement of certain of said cylinder needles into engagement with the inclined surfaces of said dial needles facing said cylinder and through said loops whereby upon retraction of said dial needles the loops carried thereby will be transferred to said certain cylinder needles.

17. In an automatic transfer knitting machine having a cylinder, cylinder needles carried by said cylinder and reciprocable axially thereof, a dial disposed adjacent one end of said cylinder at right angles to the axis thereof, dial needles carried by said dial and reciprocable outwardly and toward the axis of said dial, said dial needles being inclined to the axis of said dial whereby the transverse dimension of stitch loops received on said dial needles will be directly proportional to the angle of inclination of said dial needles, thereby permitting axial movement of certain of said cylinder needles into engagement with the inclined surfaces of said needles facing said cylinder and through said loops whereby upon retraction of said dial needles the loops carried thereby will be transferred to said certain cylinder needles.

18. A dial needle for use in an automatic transfer knitting machine comprising an elongated relatively thin body of appreciable width, a butt extending from one edge of said body, a reduced portion extending from one end of said body and terminating in a yarn engaging hook, said reduced portion being twisted about the longitudinal axis thereof, whereby when said body occupies a position inclined to the vertical said hook will occupy a vertical position, a latch pivotally mounted on said reduced portion and engageable with said hook to close the same, a shoulder on the end of said body adjacent said reduced portion, an inclined surface extending from said reduced portion to said shoulder and a tapered concave groove in one side face of said body adjacent said shoulder, whereby upon longitudinal movement of said needle a stitch loop carried by said reduced portion will move up said inclined surface into engagement with said shoulder and upon continued movement of said needle said loop will be disposed across said concave groove in a position approaching parallelism with the longitudinal axis of said needle.

19. A dial needle for use in an automatic transfer knitting machine comprising an elongated body, a reduced portion extending from one end of said body and terminating in a yarn engaging hook, said reduced portion being twisted about the longitudinal axis thereof, whereby when said body occupies a position inclined to the vertical said hook will occupy a vertical position, a latch pivotally mounted on said reduced portion and engageable with said hook to close the same, a shoulder on the end of said body adjacent said reduced portion, an inclined surface extending from said reduced portion to said shoulder and a tapered concave groove in one side face of said body adjacent said shoulder, whereby upon longitudinal movement of said needle a stitch loop carried by said reduced portion will move up said inclined surface into engagement with said shoulder and upon continued movement of said needle said loop will be disposed across said concave groove in a position approaching parallelism with the longitudinal axis of said needle.

20. A dial needle for use in an automatic transfer knitting machine comprising an elongated body, a reduced portion extending from one end of said body and terminating in a yarn engaging hook, said reduced portion being twisted about the longitudinal axis thereof, whereby when said body occupies a position inclined to

the vertical said hook will occupy a vertical position, a latch pivotally mounted on said reduced portion and engageable with said hook to close the same, a shoulder on the end of said body adjacent said reduced portion and an inclined surface extending from said reduced portion to said shoulder whereby upon longitudinal movement of said needle a stitch loop carried by said reduced portion will move up said inclined surface into engagement with said shoulder and upon continued movement of said needle said loop will be disposed in a position approaching parallelism with the longitudinal axis of said

21. A dial needle for use in an automatic transfer knitting machine comprising an elongated body, a reduced portion extending from one end of said body and terminating in a yarn engaging hook, said reduced portion being twisted about the longitudinal axis thereof, whereby when said body occupies a position inclined to the vertical said hook will occupy a vertical position, a latch pivotally mounted on said reduced portion and engageable with said hook to close the same and a shoulder on the end of said body adjacent said reduced portion whereby upon longitudinal movement of said needle a stitch loop carried by said reduced portion will move into engagement with said shoulder and upon continued movement of said needle said loop will be disposed in a position approaching parallelism with the longitudinal axis of said needle.

22. A dial needle for use in an automatic transfer knitting machine comprising an elongated relatively thin body of appreciable width, a butt extending from one edge of said body, the plane of said butt being at an angle to the plane of said body, whereby when said body occupies a position inclined to the vertical said butt will occupy a vertical position, a reduced portion extending from one end of said body and terminating in a yarn engaging hook, a latch pivotally mounted on said reduced portion and engageable with said hook to close the same, a hood on said latch partially embracing said hook when in closed position to prevent bending of said latch out of the plane of said hook, a shoulder on the end of said body adjacent said reduced portion, an inclined surface extending from said reduced portion to said shoulder and a tapered concave groove in one side face of said body adjacent said shoulder whereby upon longitudinal movement of said needle a stitch loop carried by said reduced portion will move up said inclined surface into engagement with said shoulder and upon continued movement of said needle said loop will be disposed across said concave groove in a position approaching parallelism with the longitudinal axis of said needle.

23. A dial needle for use in an automatic transfer knitting machine comprising an elongated body, a butt extending from one edge of said body, the plane of said butt being at an angle to the plane of said body whereby when said body occupies a position inclined to the vertical said butt will occupy a vertical position, a reduced portion extending from one end of said body and terminating in a yarn engaging hook, a latch pivotally mounted on said reduced portion and engageable with said hook to close the same, a hood on said latch partially embracing said hook when in closed position to prevent bending of said latch out of the plane of said hook, a shoulder on the end of said body adjacent said reduced portion, an inclined surface extending from said reduced portion to said shoulder and a tapered concave groove in one side face of said body adjacent said shoulder whereby upon longitudinal movement of said needle a stitch loop carried by said reduced portion will move up said inclined surface into engagement with said shoulder and upon continued movement of said needle said loop will be disposed across said concave groove in a position approaching parallelism with the longitudinal axis of said needle.

24. A dial needle for use in an automatic transfer knitting machine comprising an elongated body, a butt

extending from one edge of said body, the plane of said butt being at an angle to the plane of said body, whereby when said body occupies a position inclined to the vertical said butt will occupy a vertical position, a reduced portion extending from one end of said body and terminating in a yarn engaging hook, a latch pivotally mounted on said reduced portion and engageable with said hook to close the same, a shoulder on the end of said body adjacent said reduced portion, an inclined surface extending from said reduced portion to said shoulder, and a tapered concave groove in one side face of said body adjacent said shoulder, whereby upon longitudinal movement of said needle a stitch loop carried by said reduced portion will move up said inclined surface into engagement with said shoulder and upon continued movement of said needle 15 said loop will be disposed across said concave groove in a position approaching parallelism with the longitudinal axis of said needle.

25. A dial needle for use in an automatic transfer knitting machine comprising an elongated body, a butt 20 extending from one edge of said body, the plane of said butt being at an angle to the plane of said body, whereby when said body occupies a position inclined to the vertical said butt will occupy a vertical position, a reduced portion extending from one end of said body and terminating in a yarn engaging hook, a latch pivotally mounted on 25 said reduced portion and engageable with said hook to close the same, a shoulder on the end of said body adjacent said reduced portion and an inclined surface extending from said reduced portion to said shoulder, whereby upon longitudinal movement of said needle a stitch loop carried by said reduced portion will move up said inclined 30 surface into engagement with said shoulder and upon continued movement of said needle said loop will be disposed in a position approaching parallelism with the 35 longitudinal axis of said needle.

5 26. A dial needle for use in an automatic transfer knitting machine comprising an elongated body, a butt extending from one edge of said body, the plane of said butt being at an angle to the plane of said body, whereby when said body occupies a position inclined to the vertical said butt will occupy a vertical position, a latch pivotally mounted on said reduced portion and engageable with said hook to close the same and a shoulder on the end of said body adjacent said reduced portion, whereby upon longitudinal movement of said needle a stitch loop carried by said reduced portion will move into engagement with said shoulder and upon continued movement of said needle said loop will be disposed in a position approaching parallelism with the longitudinal axis of said needle.
